UNITED STATES PATENT OFFICE

GEORGE H. PERKINS, OF WELLESLEY, MASSACHUSETTS, ASSIGNOR TO POWDRELL & ALEXANDER, INC., OF BOSTON, MASSACHUSETTS, A CORPORATION OF MASSACHUSETTS

DESIGN FOR A TEXTILE FABRIC

Application filed May 16, 1929. Serial No. 31,251. Term of patent 3½ years.

To all whom it may concern:

Be it known that I, GEORGE H. PERKINS, a citizen of the United States of America, residing in Wellesley, in the county of Norfolk and Commonwealth of Massachusetts, have invented a new, original, and ornamental Design for Textile Fabric, of which the following is a specification, reference being had to the accompanying drawing, forming part thereof.

The figure is a face view of the fabric.

The design is carried forward over the sur-

face of the fabric in accordance with the representative illustration in the drawing, there being alternate rows of the respective motifs in their alternate relation shown.

I claim:

The ornamental design for a textile fabric as shown and described.

Signed by me at Boston, in the county of Suffolk and Commonwealth of Massachusetts, this 15th day of May, 1929.

GEORGE H. PERKINS.
